UNITED STATES PATENT OFFICE.

FRANK C. SOPER, OF CHICAGO, ILLINOIS, ASSIGNOR TO THE LUXFER PRISM PATENTS COMPANY, OF SAME PLACE.

DESIGN FOR A VAULT-LIGHT.

SPECIFICATION forming part of Design No. 30,472, dated April 4, 1899.

Application filed February 2, 1898. Serial No. 668,891. Term of patent 14 years.

To all whom it may concern:

Be it known that I, FRANK C. SOPER, a citizen of the United States, residing at Chicago, in the county of Cook and State of Illinois, have invented a certain new and useful Design 5 for a Vault-Light, of which the following is a description.

My invention relates to a new and original design for vault-lights, and is illustrated in 10 the accompanying drawings, wherein—

Figure 1 is a side elevation of a vault-light embodying my design. Fig. 2 is a front view 15 of the vault-light shown in Fig. 1. Fig. 3 is a plan view of the vault-light shown in Fig. 1.

Like letters refer to like parts throughout the several figures.

Referring to the drawings, the vault-light consists of a body portion A, provided with

downwardly-projecting prisms B, said prisms provided on their end surfaces with the diagonal projections or prisms C. The shape, size, and inclination of the large prisms and the projections or prisms C indicate my invention, the essential feature of which is a vault-light provided with a body portion having 20 downwardly-projecting prisms, provided on their end surfaces with diagonal projections or prisms. 25

I claim—

The design for a vault-light substantially 30 as herein shown and described.

FRANK C. SOPER.
